UNITED STATES PATENT OFFICE.

GEORGE S. CLARK, OF PORTSMOUTH, OHIO.

LAMP HOLDER FOR CAPS.

Application filed April 26, 1924. Serial No. 709,268.

The object of this invention is to provide a lamp support for miners' caps by the use of which the lamp will be firmly supported on the cap.

5 A further object is to simplify and improve the construction disclosed in my co-pending application, Serial No. 647,139, filed June 22, 1923.

In the drawings:

10 Figure 1 is a side elevation of my device applied to a cap and holding a lamp.

Figure 2 is a front elevation with the lamp removed.

Figure 3 is a sectional view on the line 15 3—3 of Figure 2.

Figure 4 is a detail sectional view approximately on the line 4—4 of Figure 3.

Figure 5 is a view similar to Figure 1, but illustrating a slight modification.

20 Figure 6 is a front elevation thereof, the lamp being removed.

Figure 7 is a sectional view approximately on the line 7—7 of Figure 6.

Figure 8 is a fragmentary sectional view 25 on the line 8—8 of Figure 7.

Figure 9 is a side elevation of a slight modification.

Figure 10 is a bottom plan view thereof.

Referring now to the drawings in detail, 30 C indicates the cap, and V the visor thereof.

The cap is of the ordinary construction worn by miners, and the miner's lamp, indicated by the character L, is also of the usual construction, the same being provided on its rear with a hook H and with a horizontally extending double ended clip I.

35 Riveted to the visor V, at the front and center thereof, there is the angle end of an elongated fiber sheet 1. Secured, preferably by rivets, to the upper and outer face of the strip 1 there is the straight outer plate 2 of a metal bracket. The plate has its upper end bent outwardly and the extremity thereof is rounded upon itself, as at 3, and from

40 thence continued rearwardly, at right angles to the plate 2 to provide the flange portion 4 of the bracket. The flange 4 is arranged over and is riveted or otherwise secured to the top of the cap C.

45 If desired, the rounded outer edge of the bead 3 of the bracket may receive therein a spring influenced rod, similar to the rod disclosed in my referred to application, Serial No. 647,139. The bead 3 is centrally formed with a notch 5. The walls provided

by the notch are preferably flared inwardly, the inner walls being rounded. In a line with the notch the upper plate or flange 4 of the bracket is provided with an elongated opening 6 which terminates approximately 60 in a line with the outer face of the cap C.

On the vertical plate 1 of the bracket there is secured a small metal plate which is rounded downwardly and directed toward the cap. This plate, indicated by the numeral 7, has its free end centrally formed with a notch 8. The arched plate 7 provides one of the elements of a catch for the hook H of the lamp L.

65 The second element is also in the nature of a metal plate 9, the same having an angle end 10 which is riveted or otherwise secured to the under face of the flange 4.

70 The plate 9 is disposed at an inward inclination with respect to the fiber sheet 1, and while out of contact with the plate 7, partly bridges the notch 8 therein.

75 The inner wall provided by the notch 8 in the clamping plate is disposed slightly out of line with the inner wall provided by the opening 6 in the plate or flange 4 of the bracket.

70 The hook H of the clamp is received in the notch 5 and the beak or pointed end thereof is passed through the opening 6. The end of the beak is passed through the notch 8 85 in the clamping element 7 and is engaged by the angularly disposed plate 9. The plate 9, being of metal, has an inherent resilience and will exert a tension against the hook to more effectively force the beak there-

90 of into frictional contact with the inner wall of the notch 8, and likewise hold the central rounded portion of the hook firmly in the notch 5.

95 The double ended clamp I is brought to engage with the edges of the fiber sheet 1, and in this manner the lamp is effectively supported on the cap. The lamp may be easily removed when desired, as will be apparent.

100 The above construction refers to Figures 1 to 4 inclusive. In the remaining figures of the drawings, the construction is substantially similar, except that the outer plate

110 11 of the clamp, at its juncture with the upper horizontal plate 12 is formed with a flat, instead of a hollow rounded bead. This bead, indicated by the numeral 14, is centrally notched, as at 15, and the horizontal plate of the brackets is formed with an opening 16 in a line with the notch 15. Secured

upon the inner face of the vertical plate of the bracket there is a clamping member 17, similar to the clamping member 7. This member, like the member 7, is arched or rounded downwardly toward the front of the cap and has its end notched, as at 18. The notch is disposed slightly beyond the opening 16. Thus it will be noted that when the hook is received in the notch and passed through the opening and also received in the notch 18 of the metal and consequently spring clamp 17, the said clamp will influence the beak of the hook in a direction toward the cap, effecting a binding action between the said clamp and the inner wall of the opening 16, and consequently moving the hook into tight engagement with the inner wall of the notch, so that the lamp will be firmly supported on the cap to prevent the liability of its being shaken or dropped off of the said cap.

With my present improvement, the double end clamp I may be employed but is not an absolute requirement, as the spring clamp means and the particular and peculiar manner in which they engage the hook of the lamp and force the same into the notch of the bead and against the inner wall of the plate-like bracket will effectively hold the lamp on the bracket without liability of lateral displacement or danger of dropping from the cap irrespective of the angle positions assumed by the miner.

In Figures 9 and 10 I have illustrated a slight modification. The angle member or bracket is similar to that above described, but the horizontal portion thereof has secured on its inner face hook clamping means which comprise two spaced comparatively small plates 19. Each of the plates has its confronting edge formed with an angle flange 20, the flange of the respective plates being directed toward each other. The flange 20 on one of the plates is of a less length than that on the other plate, and the flange on the last mentioned plate at its inner end is slit and bent over the reduced portion of the flange of the first mentioned plate as indicated by the numeral 21. The flanges are designed to clamp the hook there-

between and to force the said hook toward the bent portion or lip 21.

Having described the invention, I claim:

1. A lamp holder for caps, comprising a plate-like member secured to the top of a cap and projecting therefrom, said member having an outer notch and an opening inward of the notch, and a spring catch below the opening, arched toward the cap and having a notched end disposed slightly beyond the opening, for the purpose set forth.

2. A lamp holder for caps, comprising an angle bracket having its ends secured respectively to the top and visor of a cap and having its outer corner beaded and notched, said bracket having an opening through its upper plate inward of the notch and an arched spring clamp member secured to the bracket, directed downwardly below the opening toward the cap, and having a notched end disposed beyond the opening and a second catch member comprising a flat spring plate secured to the bracket and having its ends disposed over the notched end of the arched clamp member, for the purpose set forth.

3. The combination with a lamp having a supporting hook and a projected double ended clip below the hook, of a holding device for the lamp designed to be attached to a miner's cap and comprising an angle bracket having its outer corner beaded and notched and having an opening inward of the notch to receive the hook of the lamp therethrough, and said bracket designed to be engaged by the ends of the hook, an inwardly arched plate on the inner face of the bracket notched to receive the hook therein and to force the said hook into frictional engagement with the inner wall of a notch in the beaded corner of the bracket, and to likewise force the clip into similar engagement with the bracket, and a second spring carried by the bracket exerting a pressure upon the hook at a point opposite that engaged by the first mentioned hook.

In testimony whereof I affix my signature.

GEORGE S. CLARK.
